RESPIRATOR

William J. Joyce, Sturbridge, Mass., assignor to
American Optical Company, Southbridge,
Mass., a voluntary association of Massachusetts

Application June 29, 1942, Serial No. 448,924

6 Claims. (Cl. 128—146)

This invention relates to improvements in respirators and has particular reference to novel means and method of making the same.

One of the principal objects of the invention is to provide a collapsible respirator and method of making the same whereby the various parts of the respirator may be folded into compact relation with each other for ease of conveying and may be quickly and easily extended for use.

Another object is to provide a respirator of the above character having filter means arranged to provide a relatively large area of filtration in a relatively confined space when the parts are in extended relation with each other and which will permit the filter member to be collapsed and folded in compact relation with the facepiece when not in use.

Another object is to provide novel means and method of forming the face engaging portion of the respirator.

Another object is to provide a respirator of the above character with the face engaging portion shaped to fit about the nose and mouth of the wearer in such a manner as to render the respirator adaptable for use with goggles or other eye protection means.

Another object is to provide novel means and method of retaining the filter member of the respirator in extended position.

Another object is to provide a collapsible respirator of the above character whereby all the intermediate parts of the respirator will lie within the limits of the contour of the face engaging portion.

Another object is to provide a respirator of the above character which, when the filter unit is collapsed, the parts thereof will interfit with each other in folded compact relation.

Another object is to provide a respirator of the above character with a relatively rigid frame portion shaped to fit about the nose and mouth and with a relatively resilient face engaging portion and a collapsible filter unit supported by said frame member.

Another object is to provide a respirator of the above character with an exhalation valve so located as to permit the filter unit to be folded with the parts thereof in compact relation with each other.

Another object is to provide readily detachable mechanically interconnecting means for retaining the filter unit in extended position.

Another object is to provide a respirator of the above character with a filter member and

face engaging portion formed in integral relation with each other.

Another object is to provide a unitary frame member to which all the separable parts of the respirator are attached.

Another object is to provide a novel method of forming a resilient face engaging portion.

Other objects and advantages of the invention will become apparent from the following description taken in connection with the accompanying drawings and it will be apparent that many changes may be made in the details of construction, arrangement of parts and methods shown and described without departing from the spirit of the invention as expressed in the accompanying claims. I, therefore, do not wish to be limited to the exact details of construction, arrangement of parts and methods shown and described as the preferred forms only have been given by way of illustration.

Referring to the drawings:

Fig. 1 is a perspective view of the device embodying the invention;

Fig. 2 is a sectional view taken as on line 2—2 of Fig. 1 and looking in the direction indicated by the arrows;

Fig. 3 is a view showing the parts of the respirator folded in compact relation with each other;

Fig. 4 is a rear perspective view of a modified form of the invention;

Fig. 5 is a fragmentary sectional view illustrating a modified form of attachment of the filter member and face engaging portion to the face frame of the respirator;

Fig. 6 is a fragmentary face view of a modified form of mechanical means for retaining the filter member in extended position;

Fig. 7 is a sectional view taken as on line 7—7 of Fig. 6;

Fig. 8 is a view generally similar to Fig. 7 of a further modification; and

Fig. 9 is a view generally similar to Fig. 5 of a further modification of the invention.

The provision of a respirator for fitting about the nose and mouth of the wearer is not new in the art. It has been usual, in the past, to so fabricate said respirators as to necessitate their being retained in the shape to which they are initially fabricated with the result that they required containers of considerable size for conveyance and were also difficult to store away or to convey on one's person when not in use. Should the respirators of the prior art become crushed they were, in most instances, no longer practical for use. The present invention, there-

50

fore, is directed particularly to the provision of a respirator whose parts may be folded in compact relation with each other to guard against injury, which will require a minimum of space in storing and which may be readily carried on one's person with little difficulty.

It is a further object to provide a respirator of this character which, when the parts are extended and when in position of use, will afford a relatively large field of vision, will permit the use of goggles or other eye protection means and will provide adequate filtration with little resistance to respiration.

Referring more particularly to the drawings wherein like characters of reference designate like parts throughout the several views the device comprises a relatively rigid frame like portion 10 shaped to fit about the nose and mouth of the wearer and to the general facial characteristics of the wearer in said vicinities. The main frame-like portion 10 may be formed of any suitable rigid or nearly rigid material such as Bakelite, artificial resins, wood, relatively hard rubber or other suitable means which will tend to retain the shape to which it is fabricated.

The frame-like portion 10 has secured thereto a filter member 11. The filter member 11 may be formed of felt or any other desirable porous filtering material. The filter member 11, as shown in Fig. 2, is secured to the frame-like portion 10 by a layer of suitable cement or other adhesive 12. The cement or adhesive may be of the latex type, DuPont cement, which is a transparent cement made out of acetate material, or any other suitable cement for attaching the filter member to the frame 10. In the construction, illustrated in Fig. 2, the filter member comprises a portion 13 formed with walls which converge from adjacent the edge thereof attached to the frame 10 to a fold 14 which turns outwardly at 15 with diverging walls to a fold 16. The filter member then turns inwardly with converging walls 17 to a fold 18 which turns outwardly to diverging walls 19 to a fold 20 and thence turns inwardly with converging walls 21 which blend into a front wall 22 having an opening therein. The arrangement of the folds is such as to provide a bellows type filter member with the respective folds 16 and 20 being of a contour simulating the contour of the filter member adjacent its point of attachment with the frame 10 and being of smaller diameter so that the folds 16 will lie within the limits of the fold adjacent the point of attachment 12 and the fold 20 will lie within the limits of the fold 16, as illustrated in Fig. 3, when the filter member is collapsed and the respective folds assume an intimate compact relation with each other and with the main portion 10. The material of the filter member from adjacent its point of attachment 12 with the frame 10 is looped about the frame 10, as illustrated at 23, and has its free edge secured to the outer surface of the frame 10 by a layer of cement or adhesive 24 simulating the layer 12. The loop 23 is such as to provide a space 25 between the frame 10 and the said loop whereby the material of the loop is free to be distorted independently of the frame during use. The outer surface or face engaging surface of the loop portion 23 is provided with a coating 26 of suitable material having non-porous resilient characteristics such as latex, rubber latex, plasticized vinyl resin, Vulcaloc, milled deodorized Neoprene emulsion, (latex), prepolymerized methyl methacrylate whose polymerization is

controlled to obtain the resiliency and non-porous coating desired; ethyl cellulose plasticized with castor oil or other suitable known plasticizer; vinylidene chloride, known commercially as Saran; plasticized polyvinyl acetal; known synthetic rubbers or other means having similar characteristics for rendering said face engaging portion non-porous and resistant to water, perspiration, etc. The coating may be applied thereon to by painting, dipping, spraying, vulcanizing, or the coating material may be rendered liquid by suitable solvents and the said face engaging portion may thereafter be impregnated with said material.

15 If desired, the face engaging or loop portion 23 may be formed separately of the main filter member 11, in which instance, it would be joined to the frame 10 adjacent the joined edge 12 of the filter member. In this particular instance, 20 the loop portion 23 may be formed of rubber or of any of the materials mentioned above or may be formed of any one of said materials by milling said materials either with or without fibers or other suitable fillers, such as wood flour, zinc white, lithopone, cotton fibers, felt fibers, wool, 25 asbestos and so forth which may thereafter be fabricated to the shape of the face engaging portion and be secured to the frame portion 10 in a manner similar to that illustrated in Fig. 2.

30 In the opening in the front wall 22 there is provided a valve member 27. The valve member 27 comprises a cup-like member 28 having a peripheral flange 29 and spaced openings 30 therein. The cup-like member fits internally of 35 the opening in the front wall 22 and is secured therein by suitable pins, rivets or the like 31 which extend through the flange 29 and through a suitable internal washer 32 to clamp the material of the wall 22 between said washer and 40 flange. The cup-like member is provided with spaced pins 33 to which is attached a flap valve or the like 34. During exhalation the flap valve 34 is adapted to permit air to pass outwardly of the openings 30 and during inhalation the 45 said flap valve is adapted to be drawn into intimate relation with the adjacent wall of the cup member so as to overlie and seal the openings 30 against the entrance of air. The flange member 29, as illustrated in Figs. 1 and 2, has attached 50 thereto, on the opposed sides of the cup-like member, suitable clips or the like 35 in which the cross bar portion 36 of a brace member 37 may be snapped and interlocked therewith to retain the filter member 11 in extended position, 55 as illustrated in said figures. The brace member 37 has deflected end portions 38 pivotally attached in suitable recesses in the opposed sides of the main frame portion 10. When the filter member is collapsed, as illustrated in Fig. 3, the 60 brace bar 37 folds downwardly in compact relation with the parts. The opposed sides of the main frame member 10 are provided with loops 39 through which the enlarged ends 40 of a headband of resilient material or the like 41 are 65 threaded and thereby attached to the main frame portion 10.

70 It is to be understood that the clips 35 have suitable latch pockets or the like 42 therein into which the cross bar portion of the brace 37 may be snapped and thereby held.

In instances when the face engaging portion 23 is formed separately of the filter member 11 and is attached to the main frame 10 adjacent the edge 12 of the filter member, which is also attached to said frame member, the engaged

surface of the main frame member 10 may be increased in width to give more attaching area. In Fig. 4 there is illustrated a modification of the invention which embodies structural details generally similar to that of the respirator of Figs. 1, 2 and 3 comprising a filter member 42 simulating the filter member 11, a face engaging edge portion 43 simulating the face engaging portion 23 and a brace member 44 simulating the brace member 37. The structural details of the respirator of Fig. 4 are identical to that of the respirator of Fig. 1 except that the main frame member, simulating the frame 10, has a portion 45 looped forwardly from the initial plane of the main frame member to fit about the bridge of the nose at a lower position on the nose thereby reducing the height of the face engaging portion at said location. In the construction of Fig. 4 the forwardly looped portion 45 is so shaped as to engage the nose substantially at the base of the bony structure of the bridge of the nose and thence extend rearwardly at 46 to follow the sides of the nose at the base of said bony structure and thence turn downwardly at 47 to side portions 48 shaped to engage the cheek bones at the sides of the nose as results through the shape of the particular portions 45, 46, 47 and 48. The face engaging portion thence continues downwardly with the side portions 49 to fit about the mouth and with the lower portion 50 to fit about the chin below the mouth. The main frame portion has a face engaging edge portion 43 secured thereto which simulates the member 23. A suitable headband 51, simulating the headband 41, is adapted to hold the device on the face of the wearer. The facepiece is so dimensioned that the lower edge 50 is adapted to fit within the notch of the chin below the lower lip and by so fitting in said notch of the chin automatically positions the forwardly looped portion 45 adjacent the base of the bony structure of the bridge of the nose, particularly, in individuals having normal facial dimensions. The purpose of reducing the height of the face engaging portion at the location of the forwardly extending loop 45 is to provide greater clearance for goggles or the like which might be desirable to use in combination with said respirator.

In Fig. 5 there is illustrated a modification wherein instead of securing the portion 13 to the frame 10 adjacent the inner surface of said frame the portion 52, simulating the portion 13, is secured to the outer surface of the frame 53. It is to be understood that the said frame 53 simulates the frame 10. The material is then looped inwardly, as illustrated at 54, and has its free edge 55 secured to the inner surface of the frame 53. The said portions 52 and 55 are secured to the frame 53 by suitable layers 56 and 57, of cement or other adhesive of the type set forth herein. The said portion 54 is provided with a coating of resilient material 58 simulating the coating 26. It is to be understood that the said portion 54 may be formed separately of the portion 52 in which instance both of said portions would be secured to the portion 53 by the layer 56. The said portions 54 and 57 have abutting edges overlying the outer surface of the frame 53. In this instance, the said portion 54 may be formed of rubber or other resilient materials or may be formed in a manner similar to the portion 23 set forth above.

In Figs. 6 and 7, there is illustrated a modified form of latch member for retaining the filter member in extended position. In this instance,

the cup-like member 59, which simulates the cup 28 of the valve 27, is provided on its opposed sides with latch members 60 having inner notched surfaces. The brace 61, which simulates the brace 37, is provided with an intermediate bar portion 62 having outwardly turned portions 63 adapted to interlock with the internal notches of the latch portions 60. This is accomplished by springing the members 62 inwardly between the latch members 60 through the inherent resiliency of said portions.

In Fig. 8 there is illustrated a further modification in which instance suitable latch members 64, simulating the latch members 60, are provided having notches 65 in the outer surfaces thereof. The brace member 66 is bent so as to provide converging portions 67 which will interlock with the notches 65 of the members 64. Again this is accomplished through the inherent resiliency of the parts. The brace members 61 and 66, are secured to the main frame member in a manner generally similar to that of the brace member 37.

In Fig. 9 there is illustrated a further modification wherein the free edge 68 of the face engaging portion is secured to the frame 69 as by a layer of cement or other suitable adhesive 70. In this instance, the free edge 68 only is secured to said frame member 69. The filter material is looped as illustrated at 71 to provide a distortable face engaging portion and thence turns outwardly to a fold 72 which, in turn, blends into converging walls 73 simulating the walls 13. The outer surface of the looped portion 71 is provided with a coating 74 simulating the coating 26 and may be formed of any of the materials herein disclosed for producing the resiliency and non-porous characteristics desired.

It is to be noted that the frame members 10 and 53, at the locations of attachment of the filter member and free edge of the face engaging portions, are provided with surfaces which converge in a forwardly direction. The angle of convergence is such as to provide the proper amount of loop for the face engaging portion and yet afford maximum surface area of attachment. It is quite obvious, as the surfaces approach parallelism, the extent of the loops 23 and 24 will simultaneously decrease, that is, the loops will inherently be of a shorter radius of curvature and thereby decrease the area of contact with the face. The extent of the loop portions 23 and 54, respectively, is such as to afford a comfortable cushioning seal effect with the face.

The angle of convergence of the walls 13 is controlled in part to clear the face of the wearer, particularly, the upper wall portion 13, which must afford a clearance for the nose. It is to be noted that the upper wall portion 13 is much longer than the lower wall 13. The intent of this construction is to tilt the remainder of the filter portion in a downwardly direction to afford a wider field of vision when the device is in position of use when on the face.

It is to be understood that a construction similar to Fig. 5 may be formed, having only the free edge of the filter member secured to the frame 53 by the coating of adhesive 57. This calls for the elimination of the adhesively secured portion 56 and would constitute a construction substantially reversed to that of Fig. 9 with the portion 71 curling about the outer contour of the main frame portion instead of inwardly thereof as illustrated in Fig. 9.

From the foregoing description it will be seen that simple, efficient and economical means have

been provided for accomplishing all of the objects and advantages of the invention.

Having described my invention, I claim:

1. A device of the character described comprising a face engaging portion and a collapsible filter member connected with said face engaging portion, said collapsible filter member comprising filtering material having folded convolutions whereby said filter member may be folded in compact relation with the face engaging portion or may be extended, said filter member having an exhalation valve adjacent the forward end thereof, latch means carried by said valve member and brace means carried by the face engaging portion and having a portion attachable with said latch means for retaining the filter member in extended position.

2. A device of the character described comprising an accordion type filter member having a perforated wall in the forward end thereof and an opposed open end with a face engaging portion adjacent the edge of said end, said forward perforated wall having a valve member therein and said face engaging portion having a relatively rigid frame-like portion related therewith in such a manner as to retain the face engaging portion to a given contour shape and means carried by said face engaging portion for retaining the accordion type filter member in extended position and permitting said accordion type filter member to be folded in compact relation with the face engaging portion with the side walls of the folds in engaged relation with each other.

3. A device of the character described comprising a face engaging portion shaped substantially to fit about the nose and mouth of an individual and a cup-like filter member of relatively thin filtering material extending forwardly of said face engaging portion and terminating in an end wall, said filter member, when in extended position for clearance of the nose, having side walls converging from said face engaging portion forwardly toward the end wall with said side walls having a plurality of folded convolutions extending inwardly and outwardly relative to the direction of disposition of said side walls whereby said filter member may be collapsed to position the end wall in close relation with the face engaging portion, with the side walls of the folds in compact engaged relation with each other and with the contour of the apices of the folds lying one within the other when in said compact engaged relation and, when extended, the apices of said folds being substantially tangent with lines converging forwardly of said face engaging portion and intersecting each other forwardly of said end wall.

4. A device of the character described comprising a face engaging portion embodying a resilient portion shaped substantially to fit about the nose and mouth of an individual and a cup-like filter member of relatively thin filtering material extending forwardly of said face engaging portion and terminating in an end wall, said filter member, when in extended position for clearance of the nose, having side walls converging from said face engaging portion forwardly toward the end wall with said side walls having a plurality of folded convolutions extending inwardly and outwardly relative to the direction of disposition of said side walls whereby said filter member may be collapsed to position the end wall in close relation with the face engaging portion, with the side

walls of the folds in compact engaged relation with each other and with the contour of the apices of the folds lying one within the other when in said compact engaged relation and, when extended, the apices of said folds being substantially tangent with lines converging forwardly of said face engaging portion and intersecting each other forwardly of said end walls, the width of the upper wall of the fold nearest the face engaging portion being greater than the width of the lower wall thereof to cause the forward portion of the filter to tilt downwardly relative to the plane of the face engaging portion and means, when said filter member is extended, for retaining said filter member in said extended position to cause the forward portion of the filter to tilt downwardly relative to the plane of the face engaging portion.

5. A device of the character described comprising a face engaging portion shaped substantially to fit about the nose and mouth of an individual and a cup-like filter member of relatively thin filtering material extending forwardly of said face engaging portion and terminating in an end wall, said filter member, when in extended position for clearance of the nose, having side walls converging from said face engaging portion forwardly toward the end wall with said side walls having a plurality of folded convolutions extending inwardly and outwardly relative to the direction of disposition of said side walls whereby said filter member may be collapsed to position the end wall in close relation with the face engaging portion, with the side walls of the folds in compact engaged relation with each other and with the contour of the apices of the folds lying one within the other when in said compact engaged relation and, when extended, the apices of said folds being substantially tangent with lines converging forwardly of said face engaging portion and intersecting each other forwardly of said end wall and means, when said filter member is extended, for retaining said filter member in said extended position and for permitting said filter member to be collapsed.

6. A device of the character described comprising a face engaging portion embodying a resilient portion shaped substantially to fit about the nose and mouth of an individual and a cup-like filter member of relatively thin filtering material extending forwardly of said face engaging portion and terminating in an end wall, said filter member, when in extended position for clearance of the nose, having side walls converging from said face engaging portion forwardly toward the end wall with said side walls having a plurality of folded convolutions extending inwardly and outwardly relative to the direction of disposition of said side walls whereby said filter member may be collapsed to position the end wall in close relation with the face engaging portion, with the side walls of the folds in compact engaged relation with each other and with the contour of the apices of the folds lying one within the other when in said compact engaged relation and, when extended, the apices of said folds being substantially tangent with lines converging forwardly of said face engaging portion and intersecting each other forwardly of said end walls, the width of the upper wall of the fold nearest the face engaging portion being greater than the width of the lower wall thereof to cause the forward portion of the filter to tilt downwardly relative to the plane of the face engaging portion and means, when said filter member is extended, for retaining said filter member in said extended position and for permitting said filter member to be collapsed.

WILLIAM J. JOYCE.
